UNITED STATES PATENT OFFICE

CHARLES G. KELLOGG, OF SPRINGFIELD, OHIO, ASSIGNOR TO THE BAUER BROTHERS COMPANY, OF SPRINGFIELD, OHIO, A CORPORATION OF OHIO

SCREEN FOR SEPARATING APPARATUS

Application filed March 21, 1928. Serial No. 263,482.

This invention relates to improvements in separating apparatus in which removable screens are employed, and it more particularly relates to the construction of the 5 screening elements.

An object of the invention is to provide shaker screens which are simple in design, economical in construction and effective for the purpose for which they are intended; 10 a more specific object being to construct the screen and its frame of sheet metal as an integral unit.

In the accompanying drawing:

Fig. 1 is a plan view of a shaker screen 15 in which my improvements are embodied.

Fig. 2 is a section on the line 2—2 of Fig. 1.

Fig. 3 is an enlarged fragmentary section on the line 3—3 of Fig. 1.

20 Fig. 4 is an enlarged fragmentary section on the line 4—4 of Fig. 1.

Fig. 5 is an enlarged fragmentary bottom plan view.

Fig. 6 is an enlarged fragmentary plan 25 view.

Fig. 7 is a partial side elevation, in partial section, and reduced scale, of an apparatus in which my improved screen is embodied.

30 Fig. 8 is a section, in reduced scale, on the line 8—8 of Fig. 7.

Fig. 9 is a reduced-scale plan view of a modification of my invention.

Heretofore it has been the customary 35 practice in separating apparatus to attach the screening element proper to a wooden sash by screws, bolts or similar devices. It has also been the practice in order to accommodate the apparatus to a wide variety

40 of materials, to keep in stock a sufficient number of screening elements with perforations of different sizes and disposition to adapt the apparatus to the particular work to be performed, making it necessary to re- 45 move the screening device from time to time and substitute others. This change has been

made either by removing the screen proper from its frame and attaching another screening element to the same frame at an expen- 50 diture of considerable time in making the

change, or by having a separate frame for each screening element, the expense of which is considerable. To reduce the labor and expense resulting from such construction, I have formed the screen and its sash framing 55 integrally of sheet metal. In Fig. 1, a flat plate, 1, preferably of sheet metal having a plurality of perforations 2, in the present instance circular in shape, and having relatively wider margins than heretofore employed, is notched at the corners, as shown in Fig. 6. Each margin is given two right-angled bends, one, forming a bottom flange 3, being bent in a horizontal plane, along the dotted lines 3', and a second, forming 60 the vertical web 4, along the dotted lines 4', the previous notching permitting a mitre joint, as shown in Fig. 5. Brace members 5, preferably of sheet metal, in the present 65 case angular in section, are secured by spot-welding or other means to the bottom side of the screen 1, being so disposed that the short leg 5' of the brace 5 shall blank or 70 cover the minimum area of screening perforations. 75

Referring to Fig. 7, an apparatus of a well-known type is shown which employs shaker screens of the character to which I have referred, having a sloping shaker frame 6 pivotally supported on pivoted 80 hingers 10 permitting a reciprocatory motion. A plurality of removable shaker screens 1 are placed in the shaker frame on ledges 6, and forced one against the other by end screws 7 against a head piece (not 85 shown), lugs 8 serving to clamp the separate screens in place.

In Fig. 9 is shown a modification of my invention, it being a screen adapted to being placed preferably at the higher end of the shaker frame, the material to be screened being fed on the imperforate portion 9 from a hopper (not shown), this portion 9 serving to act as a spreader to give uniformity in depth of the material as it approaches the 95 perforations.

By this construction it will be seen that a simple and inexpensive screening unit is provided which eliminates the necessity of changing the screens proper on the wooden 100

frames or the necessity of providing a wooden frame for each screen element where a variety of such elements are employed.

Having thus described my invention, I claim:

5. 1. In a separating apparatus, a screen formed of a single piece of sheet metal having its inner portion provided with perforations and its outer portion imperforate, with its outer portions bent at right-angles to form downwardly-extending webs, the webs having their free edges bent at right-angles to form horizontal flanges, and a sheet metal brace secured to the lower side of said screen between two webs thereof, the side webs and their bent edges acting to support the element on a frame, leaving the approach to the upper surface of the element unobstructed and the end webs acting as abutments.
10. 2. In a separating apparatus, a screen formed of a single piece of sheet metal having its inner portion provided with perforations and its outer portion imperforate, with its outer portions bent at right-angles to form downwardly-extending webs, the webs having their free edges bent at right-angles to form horizontal flanges, and a sheet metal brace having a horizontal flange bent from its upper edge, said flange being secured to the under side of the perforated portion of said screen between two webs.
15. 3. In a separating apparatus, a combined screening element and sash formed from a single piece of sheet metal, said sheet of metal having perforations in its inner portions with its outer portions imperforate, said sheet also having its corners notched, vertical webs formed by bending the sides of said metallic sheet downwardly at right-angles, inwardly extending horizontal flanges formed by bending the free edges of said webs at right-angles, said notches permitting the ends of the webs and horizontal flanges to coincide, the side webs providing for supporting the elements on the frame so as to leave the approach of the upper surface thereof unobstructed and the end webs acting as abutments.
20. 4. In a separating apparatus which has a shaker frame, a combined screening element and sash of a self-sustaining character formed from a single piece of sheet metal, the metal being bent downwardly at right angles along all of its edges for stiffening purposes and to provide for supporting the element on the shaker frame so as to allow it to be readily removed therefrom, leaving the approach to the upper surface of the screening element unobstructed.
25. 5. In a separating apparatus having a shaker frame, a combined screening element and sash of a self-sustaining character formed from a single piece of sheet metal, the metal being bent downwardly along all of its edges at right angles to form webs and the free edges of the webs being bent in-

wardly at right angles to form flanges to provide for supporting the element on the shaker frame so as to allow it to be readily removed therefrom, leaving the approach to the upper surface of the screening element unobstructed and to provide end abutments.

In testimony whereof, I have hereunto set my hand this 15th day of March, 1928.

CHARLES G. KELLOGG.
